HOMER W. JONES, OF NEWARK, NEW JERSEY, AND HERMAN G. GRAUBNER, OF NEW YORK, N. Y., ASSIGNEES TO NATIONAL CARBON COMPANY, INC., A CORPORATION OF NEW YORK

BATTERY HAND LAMP

Application filed October 24, 1932. Serial No. 314,738.

This invention pertains to battery hand lamps and the like and more specifically to improved means for supporting an electric bulb in such lamps.

Ever since the electric bulbs for battery hand lamps of the focusing type have been made with filaments concentrated into a small area, considerable difficulty has been experienced in locating these bulbs in such hand lamps so the filament was at the focal point of the hand lamp reflector. Much of this trouble has been caused by the almost universal custom of screwing the threaded bulb into a conversely threaded lamp socket in the hand lamp so the end of the thread on the bulb seated against the beginning of the thread on the lamp socket. As there was usually considerable play or looseness between the outside of the threaded portion of the bulb and the inside of the threaded portion of the lamp socket, this method of seating the bulb in the lamp socket cocked the bulb to one side so it was out of alignment with the rest of the hand lamp and especially the reflector. This caused an undesirable distribution of the projected light; a light beam of low intensity; and a scattering of many of the light-rays that amounted to a loss. Therefore, one of the objects of this invention is the provision of a lamp support in a lamp socket that will hold a lamp bulb in alignment with the lamp socket and its associated reflector. Furthermore, this invention includes all the other objects and novel features hereinafter described and shown.

We attain the objects of this invention by the mechanism illustrated in the accompanying drawing, in which:

Figure 1 is a longitudinal section of a hand lamp embodying our invention.

Figure 2 is an enlarged longitudinal section of the bulb holder assembly shown in Figure 1, and

Figure 3 is an enlarged perspective of the lamp bulb seat shown in Figures 1 and 2.

One embodiment of the invention may comprise a battery hand lamp having a tubular metal casing 10 with a slightly enlarged and threaded portion 11 at the lower end over

end cap 12 having an internal groove 13 and an external groove 14. Hinged to the end cap 12 at one side of the external groove 14 is a hanger ring 15 that may be seated in the external groove 14 out of the way when not in use, and may be swung out of the external groove 14 and used as a handle, bale, or hanger ring when its use is desired. Seated in the internal groove 13 is a battery supporting and contacting member 16 having an upstanding rigid portion 17 at or near the center thereof that contacts with and supports a battery within the casing 10 that is composed of a plurality of unit dry cells 18 and 19.

Near the upper end of the casing 10 the wall thereof is bent so it forms an interior shoulder 20 and just above the interior shoulder an interior groove 21. Above the groove 21 the end 22 of the casing 10 is slightly expanded and threaded and the upper edge 23 is turned inward at a slight angle so it forms an annular plane face upon which the under side of the outturned rim 24 of the reflector 25 rests. Resting on the upper side of the outturned rim 24 of the reflector 25 is a cover glass 26 that closes the upper end of the hand lamp. The reflector 25 and the cover glass 26 are held to the upper end of the casing 10 by a bezel 27 having a threaded skirt 28 that screws over the threaded end 22 of the casing 10 and an inturned flange 29 at the upper edge thereof that extends inward over the outer edge of the cover glass 26, upon which it seats when screwed on the threaded upper end 22 of the casing 10.

Resting upon the interior shoulder 20 of the casing 10 is a circular disk of insulating material forming a diaphragm 30 that extends transversely across the casing 10 completely closing its upper end. Seated in the interior groove 21 of the casing 10 is a circular split spring ring 31 that bears against the upper side of the outer edge of the diaphragm 30 and holds it firmly against the interior shoulder 20 thereby securing it in the upper end of the casing 10. Resting against the under side of the insulating diaphragm 30 is a metal contacting plate 32 that is somewhat smaller in diameter than the diaphragm so it does not extend outward far enough to

make contact with the inner wall of the casting 10.

Secured in an aperture in the center of both the diaphragm 30 and the contacting plate 32 is a guide 33 having a hollow cylindrical sleeve 34 fitting snugly in the aperture in the diaphragm 30 and the contacting plate 32, an outwardly extending flangelike portion 35 integral with the lower end of the sleeve 34 and resting against the under side of the contacting plate 32, and a hollow cylindrical guiding member 36 integral with the outer edge of the flange 35 and extending downward therefrom. The upper edge of the cylindrical sleeve 34 is turned outward a short distance over the upper side of the diaphragm 30 thereby holding the contacting plate 32 and the guide 33 to the diaphragm 30.

Slidably mounted in the guide 33 is a bulb holder assembly 37 that supports a lamp bulb 38 in operative relation to the reflector 25. Located around the outside of the bulb holder assembly 37 and inside the guide 33 in a partially compressed condition between the under side of the flange 35 of the guide 33 and the upper side of a flange 42 on the bulb holder assembly is a helical retractile spring 39 that tends to hold the bulb holder assembly 37 in its lowermost position.

The bulb holder assembly 37, shown more clearly in Figure 2, comprises a cylindrical sheet metal lamp socket 40 having a threaded portion 41 near the upper end into which the threaded metal base of the lamp bulb 38 is screwed, and an integral flange 42 turned outward from the lower edge thereof. After the bulb holder assembly 37 is in turn assembled in the guide 33, the upper edge 63 of the lamp socket 40 is rolled outward, as shown by the dotted lines in Figure 2, so the bulb holder assembly 37 will not be forced downward out of the guide 33 by the pressure of the retractile spring 39 when the bulb holder assembly 37 is not supported by one of the unit cells of the battery. Snugly fitting within the lower part of the lamp socket 40 is a cylindrical sheet metal lamp support 43 having a narrow in-turned annular flange 44 at the upper end thereof that forms a flat seat for the outer portion of the bottom of the metal base of the lamp 38, and an outturned flange 45 at the bottom thereof that has the same outer diameter as the flange 42 of the lamp socket 40 against the under side of which the flange 45 rests. Both the front and back portions of the lower part of the cylindrical wall of the lamp bulb support 43 and the flange 45 at the bottom thereof are cut away to form clearance openings 46 for the conductor 52 that conveys current to the central terminal 53 of the lamp bulb 38, so the portions of the side wall of the support 43 and the flange 45 remaining form feet, as shown in Figure 3, that are clamped

under the flange 42 of the lamp socket 40 and hold the support 43 in the lamp socket 40.

When the lamp bulb 38 is in the lamp socket 40 and the metal base of the lamp 38 is seated on the upper side of the flange 44, the central terminal 53 of the lamp 38 extends downward through the opening in the flange 44 and makes contact with the conductor 52, so, therefore, the top of the conductor 52 is normally below the level of the flange 44 and substantially in the center of the lamp socket 40.

Resting against the under side of the flange 45 of the support 43 is a washer 47 of insulating material having approximately the same inner and outer diameters as the flange 45. Resting against the under side of the washer 47 is a conductor 48 connecting the battery and bulb and having a rim 49 somewhat smaller in diameter than the washer 47, a downwardly extending central portion 50 that makes contact with the positive terminal 51 of the uppermost unit cell 18, and an upwardly extending flexible portion 52 that makes contact with the central terminal 53 of the lamp bulb 38. The contacting member 48 is so positioned with respect to the bulb support 43 that the upstanding flexible portion 52 lies in one of the clearance openings 46 of the lamp bulb support 43. The flexible portion 52 is turned up from the body of the conductor 48 at one side thereof near the inner wall of the lamp socket 40 and, although it might clear the inner wall of the lamp support 43 if the clearance spaces 46 were not provided they do nevertheless, provide a greater margin of clearance and consequently permit greater tolerances in the manufacture of the bulb holder assembly. Resting against the under side of the rim 49 of the contacting member 48 is a washer 54 of insulating material having substantially the same dimensions as the insulating washer 47. The various component parts of the bulb holder assembly already described are held together by a member 55 having a cylindrical wall 56 that fits snugly around the outside of the flanges 42 and 45, and the washers 47 and 54, and is a loose sliding fit in the skirt 36 of the guide 33. An annular ridge 57 is formed on the inside of the cylindrical wall 56 just above the upper side of the flange 42 of the lamp socket 40, by rolling an annular groove in the outside of the wall, and this ridge in combination with the lower end of the wall 56 turned inward under the washer 54 thereby forming the inturned flange 58, clamps the component parts of the bulb holder assembly securely together. There may be an axial ridge 59 formed on the outer surface of the wall 56 of the slide 55, that slides in an axial groove of similar form on the inside of the skirt 36 of the guide 33 and prevents the lamp socket 40 from turning when a lamp bulb is screwed either into or

out of the lamp socket. As the outer diameter of the flanges 42 and 45, and of the insulating washers 47 and 54 are substantially the same they are held in alignment by the cylindrical wall 56 of the slide 55, and as the periphery of the rim 49 of the conductor 48 is smaller in diameter than the periphery of the insulating washers 47 and 54 between which it is held it, consequently, does not extend outward far enough to make contact with the inner wall 56 of the slide 55. As the downwardly extending central portion 50 of the conductor 48 fits snugly in the aperture in the insulating washer 54, and is spaced from the inner edge of the inturned flange 58 it follows, therefore, that the conductor 48 is insulated from the other metal parts of the bulb holder assembly and is, also, restricted by the insulating washers 47 and 54 so it cannot move into contact with them.

Mounted upon the outside of the casing 10 is a manually operable electric switch 60 by means of which the path of the electric current through the lamp 38 may be completed or broken at will. Attached to the switch 60 and extending upward therefrom inside the casing 10 and making contact with the bottom of the contacting plate 32 is an insulated contacting strip 61. The upper end 62 of the contact strip 61 is bent inward so the pressure of the contacting plate 32 against it bends it downward slightly and holds it in a flexed position thereby insuring a good electric contact between the contacting plate 32 and the upper end 62 of the contact strip 61. Furthermore, the contact plate 32 will always make contact with the contact strip 61 regardless of how it may be turned when it is placed in the casing 10.

When the electric switch 60 is in closed circuit position the path of the electric current through the flashlight is from the positive terminal 51 of the uppermost unit cell 18 to the contacting member 48, lamp bulb 38, lamp socket 40, guide 33, contacting plate 32, contacting strip 61, switch 60, casing 10, end cap 12, and battery support 16, to the negative terminal or bottom of the zinc containing can of the lowermost unit cell 19 in the casing 10.

The lamp bulb 38 may be reached by unscrewing the bezel 27 from the casing 10 and then removing the cover glass 26 and reflector 25 thereby exposing the lamp bulb so it may be readily grasped and unscrewed from its socket. The same lamp bulb or another one may then be screwed into the lamp socket and the reflector and cover glass replaced on the upper end of the casing and secured in place with the bezel.

When the unit battery cells 18 and 19 become exhausted they may be removed from the casing 10 by unscrewing the end cap 12 from the lower end of the casing thereby exposing the cells and removing their support

so they may drop out of the casing 10. Then new cells may be inserted in the casing 10 and the end cap 12 screwed back in place on the lower end of the casing. In case the battery cells should become swollen and stick in the casing so they will not drop out, they may be forced out from the upper end of the casing by removing the bezel 27, cover glass 26, reflector 25, spring ring 31, and the diaphragm 30 with the parts assembled thereon, thereby exposing the upper end of the uppermost battery cell 18 so it may be forced out of the casing 10 by means of any long slim object such as a screw driver or hammer handle. After the battery cells have been forced out of the casing the parts that were removed from the flashlight may be put back in the reverse order from that in which they were removed.

When the hand lamp is in operating condition the electric switch 60 may be placed in closed circuit position and the lamp bulb and reflector brought into focus by screwing the end cap 12 a little further up or down on the casing 10 thereby moving the battery support 16, battery cells 18 and 19, bulb holder assembly 37, and lamp 38, either up or down in the casing 10 until the filament of the lamp 38 and the focal point of the reflector 25 are in coincidence. If the beam of light projected from the hand lamp is watched during the focalizing operation, it may be determined from the character of the beam when a focus is obtained as the size of the beam decreases as a focus is approached so, therefore, all that is necessary is to move the focalizing adjustment until the smallest possible beam of light is secured.

Various changes may be made in the style, form, construction, and arrangement of the various parts of the hand lamp shown herein without departing from the spirit of the invention or sacrificing any of the rights thereunder.

We claim:

1. A lamp socket for a flashlight having a reflector; said lamp socket being in axial alignment with said reflector and having an outturned flange; a lamp in said lamp socket; and a lamp support having a cylindrical body in said lamp socket, an outturned flange with portions cut away and the remaining portion attached to the flange of said lamp socket, and an annular inturned flange upon which said lamp is seated so it is held in axial alignment with said reflector and lamp socket.

2. A lamp socket for a flashlight having a reflector; said lamp socket being in axial alignment with said reflector and having a flange turned outward from the bottom thereof; a lamp in said lamp socket; and a lamp support having a hollow cylindrical portion fitting snugly within said lamp socket, a flange with opposite sides thereof cut away turned outward from the bottom of said cylindrical portion and resting against the

under side of the outturned flange on said lamp socket, and a narrow annular flange turned inward from the upper end of said cylindrical portion upon which said lamp is seated so it is held in axial alignment with said reflector and lamp socket.

3. A lamp socket for a flashlight having a reflector; said lamp socket being in axial alignment with said reflector and having an outturned flange integral therewith; a lamp having a central terminal and a metal base in said lamp socket; a conductor carried by said lamp socket and making contact with said central terminal; and a lamp support having a hollow cylindrical portion fitting snugly within said lamp socket, an outturned flange at the bottom of said cylindrical portion and resting against the under side of the flange on said lamp socket, and a narrow in-turned flange at the top of said cylindrical portion upon which said metal base is seated and through which said central terminal extends downward, the opposite sides of said cylindrical portion and the flange at the lower end thereof being cut away to form clearance for said conductor.

In testimony whereof, we affix our signatures.

HOMER W. JONES.

30 HERMAN G. GRAUBNER.
